ROLLER SKATE HAVING RESILIENTLY
MOUNTED WHEEL TRUCKS
Caesar Novara, 3920 Bronx Blvd., Bronx, N.Y.
Filed May 29, 1962, Ser. No. 193,542
2 Claims. (Cl. 280—11.28)

This invention relates to a roller skate and more particularly to a resiliently mounted skate either for attachment to a permanent shoe-roller skate combination as is commonly used in indoor roller skating arenas or for roller skates which are attachable and detachable from ordinary street shoes.

A principal object of the present invention is the provision of a roller skate having a resilient material, such as rubber, fixed between the shoe supporting plate and the hanger for the wheel. This resilient material located in a particular position functions as a shock absorber resulting in more comfortable and safer skating.

Another object of the present invention is to provide improved results in skating comfort with little alteration in the present skate design.

A further object of the present invention is the provision of a simplified means for securing the elements of the skate together, the entire assembly being inexpensive to manufacture and reliably effective for the purpose intended.

The above and other features, objects and advantages of the present invention will be fully understood from the following description considered in connection with the accompanying illustrative drawings.

FIG. 1 is a side elevation of the roller skate embodying the teachings of my invention, and having a rear wheel removed for the purpose of clarity.

FIG. 2 is a front elevation view thereof and

FIG. 3 is a bottom plan view of the roller skate construction embodying the present invention.

In the drawing, the roller skate constructed in accordance with the present invention comprises a shoe supporting plate 10 which has the general configuration of a shoe sole and heel combination, and on the underside thereof is provided with hemispherical integral portions 12. It should be noted that the plate 10 may be affixed permanently to a roller skating shoe by means of rivets, adhesives or such (not shown), or the plate may be attachable and detachable from ordinary street shoes. Both of these roller skating devices are well known and a further description thereof is considered unnecessary. A substantially hemispherical or cup-shaped and resilient element 14 which is preferably constituted of rubber is located between the hemispherical portions 12 of the shoe supporting plate 10 and the cup-shaped upper portions 18 of the wheel hangers 16 and is in intimate engagement therewith. The usual roller skate wheels 20 are rotatably mounted on axles 22, the latter being securely held in the wheel hangers 16.

Each of the wheel hangers 16 is secured to the shoe supporting sole plate by means of a stud 24 passing through openings 26 and 28 in the resilient element 14 and the wheel hanger 16 and threaded at 30 into the hemispherical portion 12 of the plate 10. The stud 24 is held in place by means of a ball washer 32 and a lock nut 34. Thus, the stud 24 is at an angle of about 30° to the plane of plate 10 and is located off-center from the hemispherical portion 12 and cup-shaped upper portion 18. This arrangement permits only a restricted rotational movement of the wheel hangers 16 and wheels 20 about the stud 24.

The rubber or resilient element 14 functions as a shock absorber which absorbs shock in all directions (360°) due to its cup-shaped or hemispherical construction. Thus,

2

a shock-cushioning action is obtained by means of the use of a resilient element, such as rubber and with the configuration shown, at the location between the cup-shaped upper portion 18 of the wheel hanger 16 and the hemispherical integral portion 12 of the shoe supporting plate 10. This results in a more comfortable and safer skate. Of course, other resilient material for example, plastics in the form of synthetic rubber, such as butyl rubber, and elastomers, such as silicone rubbers may be utilized as the cushioning, resilient material 14. It should be apparent that the wheel hanger 16 for each of the wheels 20 will absorb the vertical movement as well as the torque of the wheels when they encounter bumps or holes on the skating surfaces.

15 While I have shown and described the preferred embodiment of my invention, it will be understood that the latter may be embodied otherwise than as herein specifically illustrated or described and that in the illustrated embodiment certain changes in the details of construction and in the arrangement of parts may be made without departing from the underlying idea or principle of the invention within the of the appended claims.

What I claim:

1. A roller skate comprising a shoe supporting plate having a pair of spaced hemispherical portions on the underside thereof, a wheel hanger for each of said hemispherical portions being provided with a cup-shaped upper portion conforming to the configuration of the adjacent hemispherical portion, a cup-shaped resilient element located between and abutting said hemispherical portion and said cup-shaped upper portion of the wheel hanger whereby the shock transmitted from the wheels of the skate to the shoe supporting plate is cushioned by said resilient element, and a stud and lock nut combination 25 securing said wheel hanger, resilient element and shoe supporting plate together, said stud being located off-center relative to the vertical center of said hemispherical portion and at an angle of about 30° to the longitudinal center line of said shoe supporting plate of the roller skate.

2. A roller skate comprising a shoe supporting plate having a pair of spaced hemispherical portions on the underside thereof, a wheel hanger for each of said hemispherical portions being provided with a cup-shaped upper portion, a cup-shaped resilient member located in abutting relationship between said cup-shaped upper portion of the wheel hanger and said hemispherical portion thereby conforming in configuration to both the former and latter whereby the shock transmitted by the wheels of the skate to the shoe supporting plate in all directions is cushioned by said resilient element, and a stud and lock-nut combination securing the cup-shaped upper portion of each wheel hanger to an adjacent hemispherical portion of said shoe supporting plate, said stud and lock-nut combination each 45 being located between said wheels and converging toward each other, each of said studs being positioned at an angle of approximately 30° to the longitudinal center line of said shoe supporting plate of the roller skate.
